UNITED STATES PATENT OFFICE.

JEAN VAN MELLE, OF DUBUQUE, IOWA.

RUBBER HEEL.

Application filed April 18, 1922. Serial No. 554,690.

To all whom it may concern:

Be it known that JEAN VAN MELLE, a citizen of the United States, residing at Dubuque, in the county of Dubuque and State 5 of Iowa, has invented certain new and useful Improvements in Rubber Heels, of which the following is a specification.

My invention relates to a resilient heel for shoes, and has for its primary object to 10 provide a resilient tread adapted to be applied to the heel of a shoe, which will afford in a marked degree the desirable qualities of resiliency, durability, evenness of wear and afford security to the wearer against slipping.

In the construction of rubber heels, great 15 objection has been found to same, on the ground that same do not prevent slipping, also the fact that within a short time after 20 being applied to the heel of the shoe, begins to wear on the rear of same, which results in buying of a new pair of heels or wearing a shoe that gives the wearer an uneven footing. I have designed my rubber heel to 25 avoid these objectionable features, by inserting a rotary rubber plug within the body of the rubber heel and having the rotary plug extend a slight distance beyond the tread surface of the body of the rubber heel, and 30 having the surface of the rotary tread portion provided with a corrugation or serrated face, to prevent slipping on wet pavements, etc. By the use of the rotary plug, the same can be rotated when one part wears 35 which is always adjacent the rear of the heel, to bring an unused part of the rotary plug into position adjacent the rear of the heel.

A further object of my invention is to provide a rubber heel of the above described 40 character, that is simple in construction, easily attached to the heel of a shoe, durable, efficient for the purpose intended and one that can be manufactured and placed on the market at a relatively low cost.

These and like objects of my invention 45 will be better understood as the description proceeds, and as is specifically pointed out in the appended claim.

Referring to the accompanying drawing, 50 which forms a part of this specification,

Figure 1 is a plan view of the bottom or tread portion of my improved rubber heel.

Figure 2 is a sectional view of the pre-

ferred embodiment of my invention applied to the heel of a shoe.

Figure 3 illustrates in section the various parts of which the rubber heel is composed of.

Figure 4 is a plan view of the metallic plates positioned between the rubber heel 60 and the heel of the shoe.

Referring to the drawings in detail, like numerals will be used to designate like parts in the different views.

The numeral 1 indicates a shoe of the 65 usual construction that is supplied with the usual leather heel 2. The numeral 3 designates as a whole my improved rubber heel, which consists of a rubber body 3' that is so shaped as to conform to the tread portion 70 of the leather heel, and the rubber body 3' is provided with a circular opening 4 extending all the way through the same and the said opening is located adjacent the rear of the rubber body. A metal plate 5 which 75 is of such shape as to conform to the shape of the leather heel 2 and the rubber heel 3, is positioned between the two and is provided with openings 6, that are adapted to align with openings 7 in the rubber body 3', 80 so that nails or other fastening means may be driven through the rubber heel and metal plate into the leather heel 2 of the shoe. The periphery of the metal plate 5 is provided with a series of V-shaped tongues struck 85 out of same and bent at right angle to the plate 5. These tongues 8 are adapted to be molded within the rubber body 3', as indicated at 9.

A circular rubber plug 10, that is provided with a serrated tread portion 11, is inserted within the circular opening 4 from the rubber body 3', and is secured therein by means of a star shaped plate 12 and a screw 12', which is positioned within a recess 13 95 formed in the circular rubber plug. The tread portion 11 of the circular rubber plug 10, extends a slight distance beyond the tread portion of the rubber body 3', so that the serrated edge 11 offers a firm grip to the wearer of my improved rubber heel on a 100 slippery or wet pavement. When a portion of the circular rubber plug 10 starts to wear, all that is necessary is to loosen up on the fastening screw 12', rotate the circular plug 105 around to such a position that an unworn

portion of the plug will be brought into certain position as to receive the greatest amount of wear of the heel.

In view of the foregoing description of my invention, taken in connection with the attached drawing, it is now thought that further objects or explanation as to the operation of the invention is unnecessary.

While I have shown and described the preferred embodiment of my invention, I realize that various minor changes may be resorted to, without departing from the spirit and scope of the invention as claimed, therefore, I do not wish to limit myself to the exact details of construction shown, nor to the combination and arrangement of parts.

What I claim as new and desire to protect by Letters Patent is:

In a detachable resilient shoe heel, a rubber body conforming to the shape of a heel and provided with a circular opening, a metal plate positioned on top of the rubber body, a series of V-shaped tongues struck from the metal body and molded within the rubber body, said metal plate provided with a series of openings to align with openings in the rubber body for the reception of fastening means to a leather heel, and a plug rotatable within the circular opening of the rubber body.

In testimony whereof I affix my signature.

JEAN VAN MELLE.
